UNITED STATES PATENT OFFICE.

WILEY E. CLARK, OF SAVANNAH, GEORGIA.

PENCIL-SHARPENER.

1,091,039.

Specification of Letters Patent.

Patented Mar. 24, 1914.

Application filed May 29, 1913. Serial No. 770,636.

To all whom it may concern.

Be it known that I, WILEY E. CLARK, a citizen of the United States, residing at Savannah, in the county of Chatham and State of Georgia, have invented certain new and useful Improvements in Pencil-Sharpener, of which the following is a specification.

My invention relates to cutting implements and has particular reference to means of this character for sharpening lead pencils.

An important object of this invention is to provide means of the above mentioned character, which may be employed to sharpen lead pencils of different sizes and shapes in cross-section, such as a round, square, octagonal, elliptical, or triangle.

A further object of this invention is to provide means of the above mentioned character, which are extremely simple, and are adapted to be held in the hand of the operator, while the pencil is held in the other hand, whereby such pencil may be arranged at any desired angle with relation to the cutting means, when the same is being sharpened.

A further object of my invention is to provide simple means for adjusting the cutting blade and to permit of its removal so that the same may be sharpened.

Other objects and advantages of this invention will be apparent during the course of the following description.

In the accompanying drawings forming a part of this specification and in which like numerals are employed to designate like parts throughout the same, Figure 1 is a plan view of the apparatus, Fig. 2 is a bottom plan view of the same, Fig. 3 is a plan view of the head of the apparatus, the cutting blade and associated elements being removed, Fig. 4 is an end view of the same, Fig. 5 is a plan view of the cutting blade removed, Fig. 6 is an end view of the cutting blade, Fig. 7 is a side view of an adjusting screw, and Fig. 8 is a transverse sectional view taken on line 8-8 of Fig. 1.

In the drawings, wherein for the purpose of illustration, is shown a preferred embodiment of my invention, the numeral 8 designates a handle, provided at one end only with an enlarged head 9, as shown. This head 9 is provided upon its upper inclined surface 10 with a preferably rectangular opening 11, extending longitudinally of the head.

The preferably rectangular opening 11 has oppositely arranged vertically inclined longitudinal walls 12 and 13, as shown. The opening 11 passes through the lower surface 14 of the head 9, such opening being in the form of a contracted longitudinally extending slot 15. The lower surface 14 is preferably flat. The head 9 is provided adjacent the outer edge of the vertically inclined wall 13 with a transverse recess 16, having its bottom wall 17 disposed preferably at a suitable angle to the wall 13, as shown.

The numeral 18 designates a cutting blade, the cutting edge of which extends through the contracted slot 15. This cutting blade is provided at its outer edge with spaced ears 19, disposed at an angle to the blade. The wall 17 has a screw-threaded opening 20 formed therethrough, for receiving an adjusting screw 21 carrying a head 22, as shown. This adjusting screw passes between the spaced ears 19 and is provided with a contracted portion 23, disposed adjacent the head 22, for receiving the inner portions of the ears 19. It is thus seen that by turning the operating screw 22 the cutting blade 18 will be moved so that its cutting edge will be moved into or out of the contracted slot 15. The cutting blade 18 is provided near its ends with key-hole openings 24, for receiving clamping screws 25, operating within screw-threaded openings 26 formed through the wall 13. After the adjusting screw 21 has been turned to bring the cutting blade 18 to the desired position, the clamping screws 25 are screwed up to securely lock the cutting blade in the desired position.

In the use of the apparatus, the cutting blade 18 is first adjusted to the desired position. The operator holds the handle 8 in one hand and the pencil in the other, whereby the pencil may be held at the desired angle. It is obvious that the apparatus may be readily moved for cutting or shaving the pointed end of the pencil. A particular advantage to be gained by my apparatus is that the same may be employed to cut or sharpen pencils of any size or shape in cross-section, such as cylindrical, square, elliptical or triangular. When it is desired to sharpen the blade the adjusting screw is turned to move the cutting blade 18 upwardly until the heads of the clamping screws 25 are adjacent the enlarged portions

of the key-hole openings 24, at which time the cutting blade may be readily removed by an outward movement, the same having no permanent connection with the adjusting screw 21. After being sharpened the 5 blade may be just as easily returned to its place within the opening 11 and by proper manipulation of the adjusting screw 21, be brought to the desired position.

10 It is to be understood that the form of my invention herewith shown and described is to be taken as a preferred example of the same, and that various changes in the shape, size and arrangement of parts may be 15 sorted to without departing from the spirit of the invention or the scope of the subjoined claim.

Having described my invention, I claim:

10 A pencil sharpener of the character described, comprising a handle provided at 20 one end with an enlarged head having a longitudinally extending opening formed therethrough which has one side wall there- 25 of vertically inclined and provided with a screw-threaded opening arranged near one side of the longitudinal opening, a cutting

blade slidably mounted upon the vertically inclined side wall to be moved through the lower end of the longitudinally extending opening, spaced ears attached to the outer 30 longitudinal edge of the cutting blade and disposed at an angle with relation thereto, an adjusting screw operating within the screw-threaded opening formed in the head and extending between the spaced ears and 35 having a contracted portion extending between the spaced ears, said cutting blade being provided near its opposite ends with key-hole openings having their enlarged 40 portions arranged uppermost, and clamping screws extending through the key-hole openings and operating within screw-threaded openings formed in the vertically inclined side wall of the longitudinally extending opening.

45 In testimony whereof I affix my signature in presence of two witnesses.

WILEY E. CLARK.
